TYPE LOCKING MECHANISM

Carlos Padilla, New York, N. Y., and John Mayer, Hackensack, N. J., assignors to Thriftimatic Corporation, New York, N. Y., a corporation of New York

Application May 17, 1951, Serial No. 226,911

5 Claims. (Cl. 276—1)

1

This invention relates to a type locking mechanism, more specifically to a mechanism suitable for centering and locking movable type in a holder intended for use in check imprinting machines and the like.

Many banking houses supply depositors or check service customers with blank checks personalized by having the individual's name imprinted thereon. Printing machines have been developed to permit banks to perform this imprinting with the bank's own personnel and on its own premises. The practice is to imprint individual checks and then to bind or staple them in check book form.

Each lot of checks, of course, requires that type be mounted in the machine according to the name to be imprinted, and the expedition with which this can be done largely determines the value of the imprinting machine. To facilitate the task a holder, separate from a check imprinter, but mountable therein, has been in use in which movable type may be placed. This still involves a substantial number of separate type setting and imprinting jobs, most of which must be repeated from time to time as additional check books are required.

To make repeat orders easier a holder has been devised into which movable type may be placed and then locked in position by securing a plain quad, at each end of the line of type, to the sides of the holder. Such holder with its contained, locked-in-place line of type may, after use, be filed away for subsequent reuse in a printing machine when repeat orders are received. A holder of this character is described in co-pending application Serial No. 208,147, filed January 27, 1951.

This invention involves a mechanism whereby such movable type may, after being inserted in proper order in such a holder, be mechanically centered and locked therein.

The object of this invention is to quickly and mechanically perform the foregoing operations of centering and locking.

A further object is to provide a neat, compact, reliable mechanism that may be safely and efficiently operated by unskilled labor.

In the drawings in which the same number refers to the same or a similar part:

Figure 1 is a top view of the mechanism without its case;

Figure 2 is a side view of the mechanism of Figure 1;

Figure 3 is a vertical sectional view taken on the line 3—3 of Figure 1;

2

Figure 4 is a fragmentary top view of the mechanism showing a type holder with contained type at the instant of locking;

Figure 5 is a vertical sectional view taken on the line 5—5 of Figure 1;

Figure 6 is a top view of the fully encased mechanism.

Frame 1 which supports the moving and other parts, consists essentially of base plate 2, top plate 3 and posts 4. Longitudinal slots 5 in top plate 3, shown in Figures 1, 3, and 4, accommodate vertical movable arms 20 and 21 at their upper ends and permit them to be reciprocated therein.

Carried by and at the upper ends of arms 20 and 21, as best shown in Figure 3, are opposing jaws 8, slideable on top plate 3, between guides 6. Jaws 8 straddle, in slots 9, abutment walls 36 and the ends of rail 7 which is fixed atop of and in the center of top plate 3. Referring to Figure 4 it may be seen that rail 7 provides support for type holder 34 (containing type quads 35), between the two pairs of abutment walls 36. Without type holder 34 in place, jaws 8 may freely approach each other being guided in a straight path by guides 6 and rail 7. With type holder 34 in place, jaws 8 may likewise freely approach each other but only if the holder be empty of type quads. This is so because, bridging slot 9 near the forward end of jaw 8 is cross piece 32 from which depends finger 33. Finger 33 may freely pass through the open portion of type holder 34 until it meets the end quad of a line of type. It is the means by which the movable type is pushed towards the center of the type holder. Cover plate 27, as shown in Figure 1, is provided for each jaw.

Set into holes 10 which pass through each side of each of the jaws 8 to slots 9, are points 11 carried at the inward ends of plungers 12. Plungers 12 exterior of the sides of jaws 8 are surrounded by coil springs 13 which cause points 11 to normally be in retracted position clear of slots 9. While plungers 12 bear against bars 14 they are not under such pressure as to prevent plungers 12 from sliding on the surface of bars 14 when moving, opposing jaws 8 carry them along.

Jaws 8 are actuated by handle 26 which has an arc of movement that permits reciprocating motion to be imparted through axle 24, wheel 40, pinion 23 and rack gears 22, as best seen in Figures 2 and 3. Pinion 23 is freely rotatable on axle 24 but is secured thereto through wedge carrying wheel 40 by a conventional type ball

clutch, connecting pinion 23 and wheel 40. Axle 24 is carried in journals 25. Motion of the rack gears is transmitted through arms 20 and 21 to make the movement of jaws 8 uniform in either direction.

Bars 14 are free to slide toward each other over the surface of top plate 3, being loosely engaged with top plate 3 by bracket 38 and slot 39. Bars 14 lie between a pair of plungers 12 bearing against their inner sides and clamps 15 against which they bear on their outer sides. Each clamp 15 is of one piece pivotable on axle 16 carried in journals 17. As seen best in Figure 5 the two clamps abut at their lower, inwardly curved ends under the compulsion of springs 13. To hold these lower ends a fixed minimum distance from the under surface of top plate 3, and to insure their restoration to such position, a spacing bolt 19 is threaded into the lower part of each clamp 15 and bears at its upper end against top plate 3. A pair of set screws 18 in the upper end of each branch of clamp 15 provide means for adjusting the position of each bar 14 and maintaining points 11 in proper relationship to the sides of slot 9.

To separate the abutting lower ends of clamps 15, wedge 31 is provided. Wedge 31 is carried on arm 41 which extends outward from wheel 40 so that as axle 24 rotates, it is brought between the lower ends of clamps 15, separating them and causing them to pivot on axles 16 against the resistance of springs 13. Flat shoulder 42 at the end of arm 41 and beneath wedge 31 will, upon striking wedge stop 37, stop the forward motion of handle 26.

Case 28 is provided for the device to entirely enclose the mechanism except for an opening 29 in the top of the case with a sliding cover plate 30 which may be opened to permit the insertion and removal of type holder 34.

The mechanism is used, and performs as follows:

After type holder 34 with loosely contained type quads 35 is placed atop rail 7 between abutment walls 36 and fully opened jaws 8, handle 26 is moved upward and forward bringing jaws 8 toward each other. Fingers 33 move type quads 35 toward the center of type holder 34. When the type quads are end to end and resist further movement of jaws 8, jaw movement stops and clamps 15 come into play. This occurs when pinion 23 having met substantial resistance slips out of its ball clutch connection with wheel 40 and its motion is arrested. Handle 26, however, continues to rotate axle 24 carrying with it wheel 40 and wedge 31. The wedge separates the lower ends of clamps 15 and causes them to pivot on axles 16, moving bars 14, plungers 12 and points 11 inward causing points 11 to indent the sides of type holder 34 sufficiently to lock the end quads in place.

Since finger 33 and points 11 are in fixed space relation to each other the indentations will always be made alongside the end quad. Since fingers 33 approach each other at a uniform rate of movement from starting points an equal distance from the ends of type holder 34, they will center the line of type before it is locked in place.

It is obvious that many modifications may be made in the described mechanism without departing from the scope of the invention, and therefore we do not by this description intend to limit or otherwise impair its scope.

What we claim is:

1. A type locking mechanism for centering and

locking movable type in a longitudinal, channel shaped type holder, comprising a stationary frame; provision on such frame for accommodating a type holder; a pair of opposing jaws mounted to reciprocate on such frame astride the space provided for a type holder; a finger rigidly depending from the top of each jaw rearward of its face into the center of the space provided for a type holder; a pair of movable points housed in each jaw between the face thereof and the depending finger, opposite each other across the space provided for a type holder, and transverse thereto; clamping members adapted to close on and move said points inward of said space, in any position of the jaws; jaw closing means disconnectable from the jaws when closing movement is resisted by an obstruction between the said fingers; and means for closing the clamping members after the closing movement of the jaws has ceased.

2. A type locking mechanism for centering and locking movable type in a longitudinal, channel shaped type holder, comprising a stationary frame; a rail on said frame arranged to longitudinally support a type holder, thereon; a pair of opposing jaws mounted to reciprocate on such frame astride the rail and the space provided for the type holder; a finger rigidly depending from the top of each jaw rearward of its face, and into the center of the space provided for the type holder; a pair of movable points opposite each other across the space provided for the type holder, housed transverse thereto in each jaw; clamping members adapted to close on and move said points together irrespective of the position of the jaws; jaw closing means disconnectable from the jaws when closing movement is resisted by an obstruction between the said fingers; and means for closing the clamping members after the closing movement of the jaws has ceased.

3. A type locking mechanism for centering and locking movable type in a longitudinal, channel shaped type holder, comprising a stationary frame; a rail on said frame arranged to longitudinally support a type holder in a fixed position; a pair of opposing jaws mounted to reciprocate on such frame astride and with vertical clearance of said rail; a finger rigidly depending from each jaw rearward of its face, and above and in alignment with the longitudinal axis of the rail; a pair of spring restrained opposing points housed within in each jaw between the face thereof and the depending finger, transverse to and higher than the rail; clamping members adapted to close on and press inward the said points in any position of the jaws; jaw closing means disconnectable from the jaws when closing movement of the fingers is resisted by an obstruction between them; and means for closing the clamping members after the closing movement of the jaws has ceased.

4. A type locking mechanism for centering and locking movable type in a longitudinal, channel shaped type holder, comprising a stationary frame; a rail on said frame arranged to longitudinally support a type holder in fixed position thereon; a pair of opposing jaws mounted to reciprocate on such frame, a slot parallel with the line of jaw motion, opening out at one end in the face of each jaw, adapted to accommodate the said rail and a type holder supported thereon; a rigid finger depending from each jaw in the center of each slot rearward of the face of each jaw; a hole through each jaw transverse such slot, located between the face of the jaw

and the depending finger; plungers pointed at their slot ends, housed in the holes on each side of the slot; springs to restrain the pointed ends from entering the slots; clamping members adapted to close on and press such plungers uniformly inward of the slots irrespective of the position of the jaws; a handle operably connected with jaw closing means through a ball clutch and with clamp closing means comprising a rotatable wedge adapted to close the clamping members.

5. A type locking mechanism for centering and locking movable type in a longitudinal, channel shaped type holder; comprising a stationary frame; a rail on said frame arranged to longitudinally support a type holder in fixed position thereon; a pair of opposing jaws mounted to reciprocate on such frame astride the rail; a slot in each jaw opening at one end in the face thereof, adapted to accommodate the said rail and a type holder supported thereon; a rigid finger depending from the top of each jaw in the center of each slot just rearward of the face of each jaw; a hole through each jaw transverse such slot and located between the face of the jaw and the depending finger; a plunger seated each side of the slot in such hole, with

a pointed end at the slot end and a headed end exterior of the jaw; a spring interposed between the jaw and the headed end of each plunger to restrain the pointed end from entering the slot; a movable bar lying parallel with the said rail on each side thereof in slidable contact with the adjacent pair of plunger heads; a pair of clamping members pivoted on the stationary frame, their upper ends being in closing engagement with the said bars, their lower ends curving toward each other in abutting engagement; a handle operably connected with jaw closing means through a ball clutch and operably connected through an axle and a rotatable arm with a wedge carried at the end of such arm, the path of the wedge lying in the plane of abutment of the lower ends of the clamping members, the wedge being positioned with respect to the jaw closing means to contact such lower ends of the clamping members only after the handle has passed that point on its arc of movement at which the jaws' faces could come into contact with each other.
